Kleutis N. INVENTOR.
BY
George C. Henrique, ATTORNEY.

UNITED STATES PATENT OFFICE.

KLEOFAS NAUDULAITIS, OF CHICAGO, ILLINOIS.

WINDOW ADJUSTER.

1,425,675.

Specification of Letters Patent. Patented Aug. 15, 1922.

Application filed November 30, 1921. Serial No. 518,924.

To all whom it may concern:

Be it known that I, KLEOFAS NAUDULAITIS, a citizen of Lithuania, residing at Chicago, county of Cook and State of Illinois, have 5 invented certain new and useful Improvements in Window Adjusters, of which the following is a specification.

The present invention relates to means for adjusting, balancing and fastening window sashes and it is the principal object of 10 the invention to provide a device of this kind dispensing with the use of the usual balance weight and cords.

Another object of the invention is the provision of a spirally grooved stem for the compression of a spring the strength of which is so selected that it will balance the weight of the sash and window in any of the positions thereof.

20 A further object of the invention is the provision of a means automatically operated by the movements of the sash to balance the same.

These and other objects of my invention 25 will become more fully apparent as the description thereof proceeds, and will then be more specifically pointed out in the appended claims.

In the accompanying drawing, forming a 30 material part of this specification—

Figure 1 is a top plan view of a window frame and sash equipped with a device constructed according to the present invention.

Figure 2 is a side elevation thereof partly 35 in section.

A window frame 10 has a chamber 11 formed therein, and in this chamber upper sockets 12, 13, and lower sockets 14, 15 are provided in which the correspondingly 40 shaped upper and lower ends of vertical rods 16 and 17 are rotatably held. The rod 16 intermediate its ends is formed with a thickened part 18 provided with an outer spiral groove 19 adapted to be engaged by 45 a ridge of the spirally grooved inner face of a sleeve 20 provided with a lateral tongue 21 engaging with its outer end a recess 22 of a metal socket 23 within the lower bar of the window sash 24. Between its upper end 50 and the thicker part of rod 16 the same carries a gear wheel 25 in mesh with a gear wheel 26 on rod 17.

Between gear wheel 26 and the bottom wall of chamber 11 a strong spiral spring 55 27 is wound around the rod 17 fastened with its lower end in said bottom wall and its

strength is so selected that it will balance the weight of the window sash in any of its positions. To further facilitate the up and downward movements of the sash, the same 60 is provided with a roller 28 engaging the inner edge of the window frame, while a latch 29 of any ordinary well known construction is secured to the sash and engages with its outer end in the usual manner, a 65 rack bar 30 suitably fastened to the window frame.

It will be clear that changes may be made in the general arrangement, and the construction of the minor details of my invention 70 without deviating from the scope and spirit thereof.

The device operates as follows:

If the window sash is raised, the upward movement of the same will be imparted to 75 sleeve 20 and will rotate rod 16 and its wheel 25 which in turn will rotate wheel 26 and rod 17 to tension spring 27, the strength of which is selected commensurate with the weight of the window sash, so that 80 the sash will at all times be properly balanced and only a minimum of strength will be required to operate it.

Having thus described my invention what I claim is—

1. In a device of the character described, the combination of a chambered window frame and sash with a sash balancing means comprising a plurality of sockets within the chamber of said frame, two rods rotatably 90 engaging with the upper and lower ends a pair of said sockets, a spirally grooved body on one of said rods, a means mounted on said body for rotating said rod during the raising and lowering of said sash, means for 95 transferring the rotation of said rod to the other rod, a spring wound around the other rod and secured in the bottom wall of the chamber of said frame, means for locking the sash in any of its adjusted positions, and 100 means for facilitating the up and downward movements of the sash.

2. In a device of the character described, the combination of a chambered window frame and sash, with a balancing means for 105 the sash, comprising pairwise arranged sockets, rods rotatably held in each pair of said sockets, a thickened part on one of said rods having an outer spiral groove, a sleeve adapted to move up and down on said rod 110 for rotating the same, a tongue on said sleeve adapted to be operated by the up

- and down movements of the window sash, for rotating said rod, a spiral spring on said rod having one of its ends secured on the bottom wall of the frame chamber, 5 means for imparting the rotation of one of the rods to the other, for tensioning said spring, means for locking the sash in any of its adjusted positions and rollers for facilitating the operation of the window sash.
- 10 3. In a device of the character described in combination with a chambered window frame and sash, a recessed plate secured to the sash, a pair of rods in the chamber of said frame, sockets in said chamber in which the ends of said rods are rotatably held, a strengthened part on one of said rods provided with an outer spiral groove, a sleeve 15 engaging said groove with its inner face

for rotating said rod upon traveling up and down along the same, a latch on said sleeve 20 adapted to extend into the recess of said sash plate, for compelling said sleeve to follow the up and down movements of the sash, a spiral spring wound around the other rod and secured with its lower end in the 25 bottom wall of said chamber, gear wheels on said rods for imparting to the second rod the rotation of the first rod, a roller on said sash for facilitating the handling thereof and a rack in said frame adapted to be engaged by a latch on said sash for locking the window in any of its adjusted positions.

In testimony whereof I have affixed my signature.

KLEOFAS NAUDULAITIS.
